UNITED STATES PATENT OFFICE.

WILLIAM W. DEAN, OF CHICAGO, ILLINOIS, ASSIGNOR TO KELLOGG SWITCH-BOARD AND SUPPLY COMPANY, OF CHICAGO, ILLINOIS, A CORPORATION OF ILLINOIS.

TELEPHONE TRUNKING SYSTEM.

No. 843,871.

Specification of Letters Patent.

Patented Feb. 12, 1907.

Application filed July 19, 1902. Serial No. 116,148.

To all whom it may concern:

Be it known that I, WILLIAM W. DEAN, a citizen of the United States of America, and resident of Chicago, county of Cook, and State of Illinois, have invented a certain new and useful Improvement in Telephone Trunking Systems, of which the following is a specification.

My invention relates to improvements in telephone trunking systems adapted to interconnect subscribers' lines terminating at different switchboards.

It is often desirable where communications between central offices or different switchboards are infrequent, where the distances are great, or the expense of trunk-circuits is otherwise excessive to employ trunk-circuits for establishing connections both ways—that is, for initiating connections at either end and completing them at the other. Such trunk-circuits have been provided in connection with the so-called "three-wire" systems, in which systems the cut-off relays for the lines are energized over local circuits extending throughout the switchboard and independent of the talking-circuit and the testing-terminals are connected with said local circuits; but they have not been provided with the usual apparatus employed in connection with trunk-circuits and do not operate in the usual manner. Such circuits therefore, although desirable for some reasons, are objectionable on account of introducing apparatus not of standard type and for the further reason that the operation of establishing connections differs from that ordinarily employed.

One object of my invention is to provide a trunking system adapted for reciprocal operation, which is provided with the usual and standard apparatus, and which operates in either direction in the usual manner, whereby the installation of these reciprocal circuits corresponds to the ordinary one-way-trunk circuit and the method of operation in establishing connections does not differ from the usual one-way trunk.

A further object is to provide a trunk-circuit of the kind described to operate in connection with the "Dunbar" or "two-wire" type of subscribers' lines, the distinctive features in said lines being that the cut-off relays are actuated over a portion of the talking-circuit and the testing-terminals are

connected directly with the talking-circuit, 55 whereby only two wires or cables extending throughout the switchboard are required and only two cords are used in the operators' connective circuits. With this type of line also but two-point connecting plugs and 60 spring-jacks are required.

Further objects are the provision of a simple and efficient trunking system adapted for reciprocal operation, in which special signaling devices are associated with each end of 65 the trunk to properly attend and supervise the connections.

In carrying out my invention, which has been worked out for commercial purposes, a trunk-circuit is provided with multiple- 70 switch connections at each end and also with a flexible cord and connecting-plug at each end. Provision is also made in connection with the multiple-switch sockets at each end, whereby when a connection is established at any one of the sockets the other sockets located at both ends of the trunk have their electrical condition altered so as to be in condition to test busy. Moreover, when a connection is established at one of 75 said sockets, as specified, the signaling apparatus associated with said end of the trunk is rendered inoperative, while that at the opposite end of the trunk remains in condition to operate in accordance with the plan of the 80 invention. Such signaling apparatus comprises a ringing-signal actuated when the connecting-plug is inserted in the jack or switch-socket of a subscriber's line which is rendered inoperative upon the response of the 85 subscriber and is locked out during the remainder of the connection. There is also provided a second signal, which actuates as a calling-signal when a connection has been established at one end of the trunk to attract 90 the attention of the operator at the opposite end of the trunk. A disconnect-signal is also provided for said end of the trunk, whereby when a connection has been severed at the initiating end the operator at the completing end is notified. The usual cord-circuits are provided for the operators at each switchboard.

The invention further consists in the novel arrangements and combinations hereinafter 105 described, and particularly pointed out in the appended claims, reference being had to the accompanying drawing, forming a part of

this specification, in which the same reference characters designate like parts throughout, and in which—

The figure represents a diagram of subscribers' lines terminating at different switchboards, the operators' cord-circuits at each switchboard, and the trunk-circuit extending between the switchboards.

L and L^2 indicate subscribers' lines terminating at the switchboards E and F. The subscribers' lines are of the well-known Dunbar or two-wire type, in which the cut-off relays are actuated over a portion of the talking-circuit and the testing-terminals are also connected directly with the talking-circuit. These lines are shown provided with a plurality of subscribers' stations, A and B being located on the line L, while C and D are connected with the line L^2 . As these lines are well known, further detailed description is not deemed necessary. Cord-circuits co-operating with these lines and shown at switchboards E and F are alike and are of the ordinary type used in connection with the two-wire or Dunbar line-circuits.

H indicates the trunk-circuit, extending between the switchboards E and F, this circuit comprising the line conductors 2 and 3, extending between the multiple-switch connections or jacks J J^2 , located at the switchboard E, and the corresponding connection-terminals J^3 and J^4 , placed at the switchboard F. It will be understood that as many of these jacks as is desired may be employed at each switchboard, said jacks being located before the different operators. Each jack is provided with a pair of normally open contacts 4 and 5, which when the connecting-plug is inserted in the jack are brought together by the lifting of contact 4 through the medium of the tip-spring of the jack, and thereby complete at the switchboard E from the sleeve side of the circuit the connection of the grounded cut-off relay R and at the switchboard F the circuit of the corresponding cut-off relay R^2 .

As the apparatus at each switchboard is similar, that located at one end only of the trunk-circuit will be specifically described. The cut-off relay R is provided with armatures 6 and 7, which normally connect with conductors 8 and 9, terminating in the windings w^2 and w^3 of the repeating-coil W, a condenser c being interposed between said windings and a trunk-relay r^7 being connected in parallel with said condenser. The opposite windings w^4 and w^5 are connected with an interposed condenser c^2 between the tip-strand t^3 and the sleeve-strand s^3 of the flexible cord, terminating in the corresponding contacts of the trunk-plug P^3 . The forward portion of the tip-strand t^3 is connected, through the normal contacts of the sleeve-relay r^9 , with a high-resistance test-relay r^{10} to ground, said test-relay serving when actuated to short-

circuit a portion of the operator's telephone-circuit, whereby she is enabled to receive a busy signal, and said strand is completed through the forward contacts of said sleeve-relay when the latter is actuated, the sleeve-relay being connected between the live pole of a battery B and the sleeve-strand s^3 of the trunk-cord. A tip-relay r^8 is legged to ground from the tip-strand t^3 . A ringing-signal S^4 is provided for the trunk-cord, which is rendered inoperative and locked out by means of the locking-relay r^{11} . A calling and disconnecting signal S^5 serves to indicate a call from the opposite end of the trunk when connection has been established therewith and to also give a disconnecting indication when the connection at the reverse end of the trunk has been severed. A suitable ringing-generator g^2 is provided in connection with the trunk-cord to enable the operator to call through the medium of the usual selective key either of the subscribers mounted upon a party-line or to call a single subscriber located on a line-circuit. The opposite end of the trunk-circuit is provided with similar apparatus connected with the normal contacts of the cut-off relay R^2 , a battery B^5 serving to actuate the signals and relays thereat. The cord-circuit at board E is provided with plugs P and P^2 and the associated batteries B' and B^2 , similar batteries B^3 and B^4 being connected with the cord-circuit at the switchboard F.

In the operation of the system, assuming that a subscriber on line L wishes to communicate with a subscriber on line L^2 he lifts his receiver, thus permitting current from battery B' to flow over the line-circuit and operating the line-signal S of his line in the usual way. The operator noticing the signal inserts the answering-plug P of her cord-circuit in the answering-jack of the line, thereby completing a circuit from the battery B' over the sleeve-strand of her cord-circuit through the cut-off relay R^3 to ground and actuating the same to disconnect the line signaling device and to connect the switch-socket with the limbs of the telephone-line. At the same time the supervisory relay r^3 is actuated, and the co-operating relay r^2 is likewise operated by current over the line-circuit, whereby the supervisory signal S^2 is prevented from operation. Upon learning that a subscriber located on line L^2 is wanted recourse is had to the trunk-circuit H, the condition of which is tested by means of the connecting-plug P^2 of the operator's cord-circuit. If the line is idle, it is apparent that the test-rings of the jacks of the trunk-circuit are entirely free from any source of current, and inasmuch as the tip of the testing-plug is grounded through the test-relay r^6 no click will be received by the operator. Upon finding the line idle the calling-plug P^2 is inserted in the jack of the trunk

before the operator, this act serving to lift the tip-spring of the trunk-jack to connect contact 4 with the contact 5, thereby connecting the cut-off relay R with the sleeve side of the trunk-circuit, over which a path for current from the battery B² is completed over the sleeve side of the cord-circuit, thus operating the cut-off relay, and thereby disconnecting the conductors 8 and 9, leading to the flexible cord and plug connected with that end of the trunk. The apparatus associated with the flexible end of the trunk is therefore entirely disconnected through the remainder of the connection, and all the parts associated therewith are rendered inoperative. At the same time the testing-rings at all the jacks, including those at the switchboard F, are placed in condition to test busy by current from the battery B², associated with the cord-circuit at E. It will therefore be seen that had the trunk been in use at the time the operator touched the tip of her connecting-plug P² to the test-ring of the jack before her a testing-circuit would have been completed over the tip-strand of the cord-circuit and through the test-relay r⁶, which would have short-circuited a portion of the operator's talking-circuit to cause a click in her receiver. The insertion of the connecting-plug P² serves also to operate the sleeve supervisory relay r⁵ in the cord-circuit at E, which disconnects the test-relay and completes the tip talking-strand of the cord-circuit for conversation. Simultaneously current flows to the opposite end of the trunk-circuit over conductor 3, the normal contacts of cut-off relay R², conductor 9, and through the trunk-relay r⁷, which is of high resistance, and back to the other pole of the battery B² over the tip side of the trunk-circuit and the tip cord-strand. This trunk-relay r⁷ is of sufficient resistance to prevent the actuation of the supervisory relay r⁴, located in the cord-circuit, whereby the supervisory signal S³, associated therewith, remains lighted. The actuation of the trunk-relay r⁷ closes, through its forward contacts, the circuit of the calling-signal S⁵, said circuit being traced from the live pole of the battery B² over conductor 40, through the signal S⁵, and over conductor 53 and armature 51 of the sleeve-relay r⁹ to ground. This lamp is therefore lighted, in response to which the operator depresses her listening-key k⁸ and connects her telephone with the trunk-circuit to learn the number of the party wanted. Upon obtaining this information the subscriber's line is tested by touching the tip of the trunk-plug P² to the test-ring of the adjacent jack of the subscriber's line. If the line is idle, no click will be received; but if in use the said test-rings are connected with battery, and a testing-circuit will be completed over the tip-strand 65 of the trunk-cord and through the test-relay r¹⁰, which will be actuated and will cause a click in the operator's receiver. Upon finding the line idle the plug P² of the trunk-circuit is inserted in the adjacent jack or switch socket of the line L², and the corresponding 70 socket of the line L², and the corresponding generator g² between ground and the proper line conductor, the key k⁴, which connects the generator g² with the tip-conductor, being adapted to complete a path from the battery B² over conductor 47 and including resistance 66, through the cut-off relay R³ of the line-circuit, to maintain the same operated during ringing. The sleeve-relay r⁹ is thus actuated by current from the battery B² over the sleeve-strand of the trunk-cord and 75 through the cut-off relay R³ of the line to ground. The actuation of this relay opens the circuit before traced of the calling-signal S⁵. At the same time a circuit is completed through the ringing-lamp S⁴ from the battery B² over conductor 40, through the forward contact and spring 51 of sleeve-relay r⁹, and thence over conductor 53, through the lamp S⁴ and the normal contacts of the locking-relay r¹¹. This signal is therefore 80 lighted and indicates to the operator that the called subscriber has not yet responded. 85

Upon the response of the called subscriber a low-resistance path for current from the battery B² is completed over the sleeve strand of the trunk-cord and the sleeve-conductor of the subscriber's line through the low-resistance instruments at the subscriber's station and back over the tip-conductor of the line, the tip-strand of the cord-circuit, and through 90 the relay r⁸ to ground. The latter relay therefore actuates and short-circuits the trunk-relay r⁷. The removal of the resistance of the trunk-relay r⁷ from the metallic circuit of the outgoing end of the trunk permits a sufficient flow of current therein from the battery B² to operate the tip supervisory relay r⁴ in the A cord-circuit at the station E, which has the effect of retiring the supervisory signal S³ and indicating to the A operator 95 that the called subscriber has responded. The trunk-relay armature now falls back, which completes another circuit for the lamp S⁵, which now acts as a disconnecting-signal; but the said signal is prevented from lighting 100 by reason of its second path being opened through the spring 57 of the tip-relay r⁸. This spring 57 of the tip-relay r⁸ serves to initially complete, through its forward contact, the circuit of the locking-relay r¹¹, which 105 causes the same to operate by current from the battery B² and to not only cut out the ringing-lamp S⁴, thus indicating to the B operator that the called subscriber has responded, but also to complete a locking-circuit for 110

115

120

125

130

itself through its grounded armature, which circuit can only be broken by the deenergization of the sleeve-relay r^9 . In case of crossing of the plug-contacts during the process of 5 making the connection, and thus actuating the locking-relay r^{11} , the locking-circuit is opened by the ringing-keys k^4 and k^5 , so that as soon as the ringing operation has terminated the ringing-lamp S^4 is lighted. Under 10 these conditions the subscribers are in communication, the battery B' furnishing current to the line L for talking, the battery B^2 serving to actuate the supervisory signals and relay associated with the cord-circuit 15 and the cut-off relay of the trunk, as well as to alter the electrical condition of the test-rings of the trunk-jacks, while the battery B^5 furnishes current to the called line for conversational purposes and for the operation of the 20 various relays and signals associated with the incoming end of the trunk.

At the termination of the conversation when the subscriber upon the line L returns his receiver to its hook the supervisory signal S^2 is operated in the usual manner. When 25 the called subscriber hangs up his receiver, current is cut off from the tip-relay r^8 at the end of the trunk at which the connection was completed, thus opening the short circuit 30 about the trunk-relay r^7 and completing through its spring 51 a path for current through the disconnect-lamp, S^5 . The trunk-relay, however, is immediately actuated to open the circuit of said lamp, while the resistance of the trunk-relay is so great as to prevent the continued operation of the supervisory relay r^4 . The supervisory signal S^3 associated therewith is therefore operated to indicate to the initiating operator that the 35 conversation has terminated. This operator now takes down the connection, which results in deenergizing the trunk-relay r^7 at the opposite end of the trunk, thereby completing the circuit of the disconnect-lamp S^5 from the 40 live pole of the battery B^5 over conductor 40 to spring 51 of the sleeve-relay r^9 , and thence over conductor 53 through the lamp S^5 , the armature and back contact of the trunk-relay, and the back contact and spring 57 of the tip-relay r^8 to ground. This signal is therefore 45 actuated, and then the operator at this end of the trunk withdraws the trunk-plug from the called-subscriber's line and restores all parts to normal condition.

50 It will be apparent that order or instruction circuits may be employed between the operators, if preferred; but the above operation is the one most commonly used with this arrangements of trunks.

55 In case a subscriber at exchange F wishes to communicate with a subscriber at the exchange E the connection at the office F is completed by means of the cord-circuit shown by inserting the answering-plug P in 60 the jack of the calling-line and after ascer-

taining the order by inserting the plug P^2 in one of the jacks J^3 or J^4 of the trunk-circuit H . The insertion of the cord-circuit plug into the jack of the trunk results, as described with reference to the connection at the opposite 70 end of the trunk, in actuating the cut-off relay R^2 , which disconnects the plug P^3 at that end of the trunk and its associated apparatus. The desired connection is then completed by the operator at the opposite end of the trunk, 75 who tests the condition of the called line by means of the plug P^3 of the trunk, and if the line is idle inserts the said plug into the jack of the wanted subscriber. The same operation of the ringing-signal, calling-signal, and 80 disconnect-signal takes place with reference to this end of the trunk as described with reference to the former end, whereby the answer of the called subscriber and the replacement of his telephone upon its hook actuates the 85 supervisory signal associated with the connecting end of the cord-circuit at the switchboard F .

In case the call at either of the switchboards had been for a subscriber whose line 90 terminated at said switchboard the connection would have been completed directly through the cord-circuit by means of the connecting-plug P^2 thereof.

It will be understood that when a line is 95 found busy the operator may communicate directly with the initiating operator or with the waiting subscriber, or an ordinary "busy-back" and "don't-answer" signal-circuit may be provided in connection with the 100 cords and plugs of the trunk, whereby when the corresponding condition of a called line is noted the trunk-plug may be inserted in the adjacent jack of said signaling apparatus to thereby notify the initiating operator and 105 the waiting subscriber.

The ground connections hereinbefore referred to at each of the different switchboards, it will be understood, may and in practice usually are one and the same, or they may be the common office return, although it is found by experience that it is practically necessary to place a dead ground upon one side of the common battery. It is also apparent that the other poles of the batteries may be grounded, so far as the operation of the system is concerned, the only variation necessary being to remove the present ground connections, replace them by other conductors, and place the ground-conductors upon the opposite pole of the battery.

While the exact dimensions of the relays are not the essence of my invention, I have secured good results from trunk-relays of fifteen-thousand-ohms resistance, tip and sleeve relays of one-hundred-ohms resistance and locking-relays of five hundred ohms, while the other parts may be of the usual or desirable dimensions. It is also apparent so far as some features of the invention are 130

concerned that the lines may terminate in single cords and plugs in place of the double cords shown and described and that the trunks may terminate in jacks and plugs in place of the plugs and cords. Other ways of carrying out my invention and other changes and substitutions may be made therein and still come within its scope and principle. I do not, therefore, wish to be confined in all respects to the particular construction and arrangement here shown and described. Any desired arrangement of the trunks may be had, the plugs terminating at a section by themselves, the jacks in separate banks, or any other preferred arrangement. It is also understood that the test-relays are preferably common plugs at each operator's position.

In an application filed June 28, 1902, Serial No. 113,581, I have shown and specifically described a one-way trunking system including line-circuits co-operating therewith of the type herein described, as well as a busy-back and don't-answer signaling circuit and apparatus. I do not intend herein to claim the subject-matter of the said application; but

What I do claim as my invention, and desire to secure by Letters Patent, is—

1. The combination with a trunk-circuit extending between multiple switchboards, adapted for reciprocal operation, and provided with multiple-switch connections at each switchboard; of testing-terminals for said connections connected with the talking-circuit during conversation, and means when connection is established at any of said switch connections for placing said testing-terminals at the other of said switch connections in condition to test busy, substantially as described.

2. The combination with a trunk-circuit extending between multiple switchboards, adapted for reciprocal operation, and provided with multiple-switch connections at each switchboard; of testing-terminals for said connections connected with one side of the talking-circuit during conversation, and an operator's connecting-circuit for establishing connection with one of said switch connections, and means when said connection is established for placing the said testing-terminals at all of the other switch connections in condition to test busy, substantially as described.

3. The combination with a trunk-circuit extending between multiple switchboards, adapted for reciprocal operation, and provided with multiple-switch connections at each switchboard; of testing-terminals for said connections connected with one side of the talking-circuit during conversation, an operator's connecting-circuit for establishing connection with one of said switch connections, and a source of current associated with 65 said connecting-circuit and adapted to be

connected with the trunk talking-circuit when said connection is established, whereby said testing-terminals at all of the other switch connections have their electrical condition altered and are placed in condition to test 70 busy, substantially as described.

4. The combination with a trunk-circuit extending between multiple switchboards, adapted for reciprocal operation, and provided with multiple-switch connections at 75 each switchboard; of testing-terminals for said connections, and means actuated wholly at any one of said switch connections for placing the testing-terminals at all of the other switch connections in condition to test 80 busy during conversation, substantially as described.

5. The combination with a trunk-circuit extending between multiple switchboards, adapted for reciprocal operation, and provided with multiple-switch connections at 85 each switchboard; of testing-terminals for each of said connections, a cord-circuit adapted to be connected with said connections, and a source of current associated with said cord-circuit, and means for altering the potential of all of the testing-terminals of said switch connections from said source when the said cord-circuit is connected with any of the switch connections, substantially as de- 90 scribed.

6. The combination with a trunk-circuit extending between multiple switchboards, adapted for reciprocal operation, and provided with multiple-switch connections at 100 each switchboard; of testing-terminals for said connections connected directly with one side of the talking-circuit during conversation, a cord-circuit adapted to be connected with any of said switch connections, a source 105 of current associated with the cord-circuit and adapted to be connected with the trunk-circuit when a connection is established therewith by said cord-circuit, signaling apparatus connected with the cord-circuit and adapted to be operated by said source of current, said source of current also serving to vary the potential of said testing-terminals at both ends of the trunk to place them in condition to test busy, substantially as described. 115

7. The combination with a trunk-circuit extending between different switchboard-sections and having a switch-socket and a flexible cord terminating in a connecting-plug at each end of the trunk to adapt the same for reciprocal operation in interconnecting telephone-line circuits for conversation, of operator's connective circuits at each end of the trunk to establish connections with said sockets, the said connections being completed 120 by means of the incoming cords and plugs at the opposite end of the trunk, substantially as described.

8. The combination with a trunk-circuit 125 extending between different switchboard-sec-

- tions and having multiple-switch sockets in the form of spring-jacks and a flexible cord terminating in a connecting-plug at each end of the trunk to adapt it for reciprocal operation 5 in interconnecting telephone-line circuits for conversation, of operator's connective circuits at each of said switch-sockets to establish connections therewith, said connections being completed at the opposite end of the 10 trunk through the medium of the flexible cord and connecting-plug, substantially as described.
9. The combination with a trunk-circuit extending between different switchboard-sections and having multiple-switch sockets and a flexible cord terminating in a connecting-plug at each end of the trunk-circuit to adapt the same for reciprocal operation in interconnecting telephone-line circuits for conversation, of operator's connective circuits at each end of the trunk to initiate connections between the calling-lines and said sockets, said connections being completed at the opposite ends of the trunk by connecting the trunk-cord 20 with the called-subscriber's line, and means actuated when connection is established at one of said switch connections for placing the other switch connections of the trunk in condition to test busy, substantially 25 as described.
10. The combination with a trunk-circuit extending between different switchboard-sections and having a multiple number of switch-sockets and a flexible cord terminating in a connecting-plug at each end of the trunk-circuit to adapt the same for reciprocal operation in interconnecting telephone-line circuits for conversation, of operator's connective circuits at each end of the trunk 30 to initiate connections between the calling-lines and said sockets, said connections being completed at the opposite ends of the trunk by connecting the trunk-cord with the called-subscriber's line, and means actuated wholly 40 at the section where the connection is established for placing all of the switch connections in both ends of the trunk in condition to test busy during conversation, substantially 45 as described.
11. The combination with a trunk-circuit extending between the different switchboard-sections and having a plurality of switch-sockets and a flexible cord terminating in a connecting-plug at each end of the trunk-circuit to adapt the same for reciprocal operation in interconnecting telephone-line circuits, of means for establishing connection from the calling telephone-line at either 55 switchboard with the proper switch-socket 60 of the trunk in initiating the connection, said connection being completed at the other end of the trunk by connecting the trunk-plug at said end with the called line, substantially as described.
12. The combination with a trunk-circuit

extending between different switchboard-sections and having a flexible cord terminating in a connecting-plug and a switch-socket in the form of a spring-jack at each end to adapt the trunk-circuit for reciprocal operation in interconnecting telephone-line circuits for conversation, of operators' connective circuits at each end of the trunk to establish connections with the said sockets, signaling apparatus at each end of the trunk, and means actuated when connection is established with one end of the trunk for disconnecting the apparatus associated with said end, substantially as described. 70

13. The combination with a trunk-circuit 80 extending between different switchboard-sections and having a flexible cord terminating in a connecting-plug and a switch-socket in the form of a spring-jack at each end to adapt the trunk-circuit for reciprocal operation 85 in interconnecting telephone-line circuits for conversation, of operators' connective circuits at each end of the trunk to establish connections with the said sockets, signaling apparatus at each end of the trunk, and 90 means actuated when a connection is established with one end of the trunk for disconnecting the apparatus associated with said end, and for actuating the said apparatus at the opposite end of the trunk, substantially 95 as described.

14. The combination with a trunk-circuit extending between different switchboard-sections and having a flexible cord terminating in a connecting-plug and a switch-socket 100 in the form of a spring-jack at each end to adapt the trunk-circuit for reciprocal operation in interconnecting telephone-line circuits for conversation, of operators' connective circuits at each end of the trunk to establish 105 connections with the said sockets, signaling apparatus at each end of the trunk, and means when a connection is established with one end of the trunk for disconnecting the apparatus and plug associated with said end, 110 substantially as described.

15. The combination with a trunk-circuit extending between multiple-switchboard sections adapted for reciprocal operation and provided with a switch connection at each 115 switchboard, a disconnect-signal at each end of the trunk normally connected therewith, and means when connection is established with one end of the trunk for disconnecting the said signal at said end, substantially as 120 described.

16. The combination with a trunk-circuit extending between switchboard-sections adapted for reciprocal operation and provided with a plug and switch at each switchboard, a disconnect-signal at each end of the trunk, and means when a connection is established at one end for disconnecting the signal and the plug at said end of the trunk, substantially as described. 125

17. The combination with a trunk-circuit extending between switchboard-sections and having a flexible cord terminating in a connecting-plug, and a switch-socket in the form of a spring-jack, at each end to adapt the trunk for reciprocal operation in interconnecting telephone-line circuits for conversation; of operators' connective circuits at each end to establish connections with said sockets, and a cut-off relay for each end of the trunk actuated when a connection is established at said end to cut off the associated trunk-plug, substantially as described. 5
18. The combination with a trunk-circuit extending between multiple switchboards and provided with a switch connection at each switchboard, of operators' connective circuits at each end of the trunk to establish connections with said connection, a cut-off relay for each end of the trunk actuated over a portion of the talking-circuit when connection is established with said end to cut off the remaining portion of the trunk at said end, substantially as described. 15
19. The combination with a trunk-circuit extending between different switchboard-sections and having a flexible cord terminating in a connection-plug, signaling apparatus, and a switch-socket in the form of a spring-jack at each end of the trunk to adapt the trunk for reciprocal operation in interconnecting telephone-line circuits for conversation; of operators' connective circuits at each end to establish connections with the said sockets, a cut-off relay for each end of the trunk actuated over a portion of the talking-circuit at said end when connection is established with any of the associated sockets to cut off the corresponding plug and signaling apparatus, substantially as described. 25
20. The combination with a trunk-circuit extending between multiple switchboards adapted for reciprocal operation and provided with switch connections at each switchboard, of a signaling apparatus at each end of the trunk, a cut-off relay at each end normally disconnected therefrom, and means when connection is established at one end to connect said cut-off relay with the trunk-circuit and to operate the same over a portion of the talking-circuit, said normal disconnection preventing the operation of the other cut-off relay by the current impressed upon the trunk-line, substantially as described. 45
21. The combination with a trunk-circuit extending between different switchboard-sections and having a switch-socket at one end and a flexible cord and connecting-plug at the other, of a signal at the end having the switch-socket to adapt the trunk-circuit for reciprocal operation, a cut-off relay associated with said socket, means for operating said relay when connection is established with said socket to render the said signal inoperative, and a supervisory relay at said 55
- socket end adapted to operate in series with said cut-off relay when a connection is established at said end, substantially as described. 60
22. The combination with a trunk-circuit extending between different switchboard-sections, of a switch-socket at one end and a flexible cord and connecting-plug at the other, a calling-signal at the end of the trunk at which the said socket is located and having its operation controlled by current from the opposite end of the trunk whereby the trunk is adapted for reciprocal operation, a cut-off relay associated with the said socket and adapted to be operated by current flowing over a portion of the talking-circuit when connection is established with said socket, said relay serving to render said signal inoperative, substantially as described. 70
23. The combination with a trunk-circuit extending between different switchboard-sections, of a switch-socket at one end of the trunk-circuit and a flexible cord terminating in a connecting-plug at the other end, a calling-signal at the socket end of the trunk having its operation controlled by the other end of the trunk whereby the trunk is adapted for reciprocal operation, a cut-off relay associated with the said socket but normally disconnected from the trunk, means when connection is established with the said socket to connect the coil of said cut-off relay with one side of the talking-circuit of the trunk and to operate the same, said latter relay serving when operated to render said signal inoperative and a supervisory relay at said socket end adapted to operate in series with said cut-off relay when a connection is established at said end, substantially as described. 85
24. The combination with a trunk-circuit extending between different switchboard-sections and having a flexible cord terminating in a connecting-plug and multiple-switch connections at each end to adapt the trunk-circuit for reciprocal operation for interconnecting telephone-line circuits for conversation; of a calling-signal for each end of the trunk, and means when a connection is established with the switch-socket at either end to render inoperative the signal at said end, and to actuate the signal at the other end, substantially as described. 105
25. The combination with a trunk-circuit extending between different switchboard-sections and having at one end a flexible cord terminating in a connecting-plug and multiple-switch connections at each end to adapt the trunk-circuit for reciprocal operation for interconnecting telephone-line circuits for conversation, of a calling-signal for each end of the trunk, a cut-off relay for each end of the trunk-circuit adapted to be actuated over a portion of the talking-circuit when connection is established with the switch-sockets, said relay serving to render the calling-signal at the same end of the trunk inoperative, and a supervisory relay at said 120
- 65

- erative, and means for actuating the calling-signal at the other end of the trunk-circuit as soon as the connection is established, substantially as described.
26. The combination with a trunk-circuit extending between different switchboard-sections and having a flexible cord terminating in a connecting-plug and multiple-switch connections at each end to adapt the trunk-circuit for reciprocal operation for interconnecting telephone-line circuits for conversation, of a calling-signal for each end of the trunk, a cut-off relay at each end of the trunk-circuit normally disconnected therefrom, means for connecting said relay with one side of the trunk-circuit and actuating it by current thereover when connection is established with one of the switch-sockets, said relay serving to render the signal at the same end inoperative, while the signal at the other end is operated upon the establishing of the said connection, substantially as described.
27. The combination with a trunk-circuit extending between different switchboards adapted for reciprocal operation, and provided with multiple-switch connections at each switchboard; of a ringing-signal at each end of the trunk to indicate the response of the called subscriber at the end employed as the incoming end, and means for rendering inoperative the similar signal at the other and outgoing end of the trunk, substantially as described.
28. The combination with a trunk-circuit extending between different switchboards, adapted for reciprocal operation and provided with multiple-switch connections at each switchboard; a ringing-signal at each end of the trunk to indicate the response of the called subscriber at the end employed as an incoming end of the trunk, means for rendering inoperative the similar signal at the other and outgoing end of the trunk, and means for locking out the first signal at the incoming end during the remainder of the connection, substantially as described.
29. The combination with a trunk-circuit extending between different switchboards, adapted for reciprocal operation in connecting subscribers' lines for conversation, and provided with multiple-switch connections at each switchboard; of a ringing-signal at each end of the trunk to indicate the response of the called subscriber at the end employed as an incoming end, a disconnect-signal at each end of the trunk to indicate at the incoming end when the connection has been severed at the end employed as the outgoing end of the trunk, and means for rendering the corresponding signals inoperative at the outgoing end when connection is established at said end of the trunk, substantially as described.
30. The combination with a trunk-circuit extending between different switchboard-sections, adapted for reciprocal operation, and provided with multiple-switch connections at each switchboard; of a ringing-signal at each end of the trunk to indicate the response of the called subscriber when the end is employed as an incoming end, a disconnect-signal at each end of the trunk to indicate at the said incoming end when connection has been severed at the corresponding outgoing end of the trunk, means for locking out said ringing-signal at the incoming end after the subscriber has responded, and means for rendering the corresponding signals inoperative at the outgoing end when connection is established with the trunk, substantially as described.
31. The combination with a trunk-circuit extending between different switchboards adapted for reciprocal operation and provided with both switch connections and plugs at each switchboard; of a signal at each end of the trunk, means for disconnecting the signal at the outgoing end of the trunk when connection is established with said end in initiating a connection, the signal at the other end of the trunk being actuated at such time to indicate a call, said latter signal also serving as a disconnect-signal when the conversation has terminated and the connection with the trunk has been severed at the initiating end, substantially as described.
32. The combination with a trunk-circuit extending between different switchboards and having multiple-switch sockets and a connecting-plug at each end to adapt a circuit for reciprocal operation, a socket at one end and a plug at the other being employed in each connection for conversation, of means associated with each plug to indicate when a connection has been established with a socket at the opposite end and at the close of the conversation, when the connection has been severed at said socket, and means for disconnecting the plug and associated apparatus at the same end as the said socket when connection is established therewith, substantially as described.
33. The combination with a trunk-circuit extending between different switchboards and terminating in both multiple-switch sockets and a connecting-plug at each end to adapt the circuit for reciprocal operation, a socket at one end and a plug at the other being employed in each connection for conversation, means associated with each plug to indicate when a connection has been established with a socket at the opposite end of the trunk, the said sockets at both of said ends being placed in position to test busy when the connection has been established at one of said sockets, and means for disconnecting the plug and associated apparatus at

the said socket end of the trunk when the connection is established, substantially as described.

34. A trunk-circuit extending between different switchboards and having multiple-switch sockets and a connecting-plug at each end to adapt the circuit for reciprocal operation, a socket at one end and a plug at the other being employed in each connection for conversation; of means associated with each plug to indicate when a connection has been established at a socket at the opposite end of the trunk and, at the close of the conversation, when the connection has been severed at said end; means associated with each plug to indicate the response of the called subscriber when the plug is employed in making the connection, and means for disconnecting the plug and associated apparatus at the opposite end of the trunk when connection is established with the corresponding socket, substantially as described.

35. The combination with a trunk-circuit extending between different switchboard-sections having multiple-switch sockets and a connecting-plug at each end to adapt the circuit for reciprocal operation, a socket at one end and a plug at the other being employed in each connection for conversation, of a signal associated with each plug to indicate when a connection has been established with a socket at the opposite end of the trunk

and at the close of the conversation when the connection has been severed at said socket, a ringing-signal associated with each plug to indicate the response of the called subscriber with which the plug is connected, said ringing-signal being prevented from again operating after the response of the called subscriber during the existence of the connection, means associated with each plug for selectively calling the subscribers upon a party-line, and further means for disconnecting the plug and its associated apparatus at the same end as the socket employed for the connection, said disconnection taking place when the connection is established therewith, substantially as described.

36. The combination with a trunk-line terminating at each end in both jacks and plugs, of cord-circuits adapted to be connected with said trunk at either end, and subscribers' lines at either end with which said trunk is adapted to connect, suitable signals for said trunk, and means whereby said signals will be suitably actuated when said trunk is used in either direction, substantially as described.

Signed by me at Chicago, county of Cook, State of Illinois, this 17th day of July, 1902.

WILLIAM W. DEAN.
